DESIGN FOR A COLOR TEMPERATURE METER CASING

Miller R. Hutchison, Jr., Rochester, N. Y.

Application October 21, 1938, Serial No. 80,583

Term of patent 14 years

To all whom it may concern:

Be it known that I, Miller R. Hutchison, Jr., a citizen of the United States of America, residing at Rochester, county of Monroe, and State of New York, have invented a new, original, and ornamental Design for Color Temperature Meter Casings, of which the following is a specification, reference being had to the accompanying drawing, forming a part thereof, in which:

Fig. 1 is a front elevational view of a color temperature meter casing showing my new design.

Fig. 2 is an edge elevational view thereof, and Fig. 3 is a rear elevational view thereof.

I claim:

The ornamental design for a color temperature meter casing, as shown.
